DESIGN FOR A TEXTILE FABRIC OR THE LIKE

Harold Slater, New York, N. Y.

Application January 16, 1942, Serial No. 105,233

Term of patent 7 years

To all whom it may concern:

Be it known that I, Harold Slater, a citizen of the United States and resident of New York city, in the county of New York and State of New York, have invented a new, original, and ornamental design for a Textile Fabric or the like, of which the following is a specification, reference being had to the accompanying drawing, forming a part thereof.

In the drawing, the figure is a face view of a piece of textile fabric showing my new design, a unit of which is enclosed substantially between

the dot and dash lines, and said unit being repeated as indicated beyond the unit boundaries.

The essential features of my design for a textile fabric reside in the specific configuration of the elements of ornamentation, including the surface ornamentation of said elements and their arrangement on a fabric as illustrated.

I claim:

The ornamental design for a textile fabric or the like, as shown and described.

HAROLD SLATER.
